UNITED STATES PATENT OFFICE.

JAMES R. BURKHARDT, OF DAVENPORT, IOWA.

VALVE.

1,169,003.

Specification of Letters Patent. Patented Jan. 18, 1916.

Application filed September 3, 1914. Serial No. 860,104.

To all whom it may concern:

Be it known that I, JAMES R. BURKHARDT, citizen of the United States, residing at Davenport, in the county of Scott and State of Iowa, have invented certain new and useful Improvements in Valves, of which the following is a specification.

This invention relates to valves, and more particularly relates to valved devices adapted to be interposed at some point in the fuel pipe leading from a source of supply to its point of consumption so that means will be thereby provided to govern the passage of the fuel.

As a principal object, this invention contemplates the provision of valved means of the character described which shall be so constructed as to form a continuous passage from the gasoline tank to the motor of a combustion engine only when properly set in a predetermined position, knowledge of which is available only to the rightful operator.

A further object is to provide in a valve of the type set forth permutation means whereby the predetermined set position of the valve may be varied at will and to also provide means whereby the person having knowledge of the correct combination may easily manipulate the valves to assume the proper position without the aid of tools.

A still further object is to provide means connected with a valve of the foregoing species which shall reliably prevent fraudulent tampering with the mechanism with an idea of preventing proper operation of the valve and to locate the actual working parts at points practically inaccessible to any unauthorized person while situating the controlling means at a point which may be found to be most desirable for the ready operation of the owner.

An object of equal importance with the foregoing is to so construct a valve of the class described and in particular to pay such regard to the proportion, number and arrangement of parts as to render it capable of being cheaply manufactured, readily installed, durable and efficient in operation.

The above and additional objects which will become apparent as this explanatory description proceeds are accomplished by such means as are illustrated in the accompanying drawings, described in the following specification and then more particularly pointed out in the claims which are ap-

pended hereto and form a part of this application.

With reference to the drawings, wherein there is illustrated the preferred embodiment of this invention as it is reduced to practice, and throughout the several views of which like characters of reference designate similar parts: Figure 1 is a sectional view taken through an automobile fuel tank showing the novel valve comprehended by this invention positioned therein and connected to the customary fuel pipe, Fig. 2 is a sectional view taken on the plane indicated by the line 2-2 of Fig. 1, Fig. 3 is a transverse section of a portion of the fuel tank as indicated by the line 3-3 of Fig. 1, Fig. 4 is a sectional view showing the device suitably positioned upon any desired support and interposed between spaced sections of the fuel pipe, Fig. 5 is a plan view of the permutation dials, parts being broken away, and Fig. 6 is a transverse sectional view taken on the plane determined by the lines 6-6 of Fig. 4.

There is illustrated in Fig. 1 a fuel tank 10 such as is to be found upon every gasoline driven vehicle in the bottom of which is formed the rectangular offset portion 11 of such size as to readily receive therein a casing 12 longitudinally bored as indicated at 13 and provided with enlarged valve seats 14 in which are seated rotary valves 15 severally bored as denoted by the numeral 16 in order to permit each of said bores to be aligned with the fixed bore 13 in providing a continuous passage therethrough. Pairs of suitable lateral flanges 17 are provided for the valve casing as indicated in Figs. 2 and 3 in order that such casing may be firmly secured in the offset portion 11 by means of suitable fastening means 18 rigidly connecting the said flanges to the bottom 19 of the fuel tanks 10 in which the offset portion 11 is formed.

Hollow bosses 20 are formed on the lower side of the valve casing 12 in a corresponding position to the valve seat 14 though oppositely disposed and are adapted to receive a reduced extension 21 of each valve 15 in order to maintain the latter in their proper position as determined by the resilient means 22 interposed between washers 23 and surrounding said reduced extensions. Valve stems 24 are provided for each of the valves 15 and are adapted to extend upwardly and protrude through a plate 25 ex-

teriorly positioned upon the tank 10 and formed with the cylindrical enlargements 26 which latter are recessed to receive plugs 27, the bottoms of which are recessed oppositely to the enlargement 26 in order to provide stuffing glands 28 to prevent the escape of the fuel by evaporation.

The exterior ends of the valve stems 24 are adapted to receive a turning member 29 whereby the stem and the valve of each stem may be rotated to produce the proper regulation of the bores 16 in conjunction with the casing bore 13. Positioned adjacently to the turning members 20 are adjustable pointers 30 formed of a collar portion and a lateral enlargement projecting from the collar portion, an adjusting screw 31 being received in a suitable aperture to the collar portion in order to bear upon the valve stem 24 and maintain the pointer 30 in its adjusted position.

For coöperation with the pointers 30 there is provided a dial such as illustrated in detail in Fig. 5 and designated in the form 25 illustrated in Figs. 1, 2 and 3 by the numeral 32, such dial being formed on the enlarged upper surface of the plate 25 and being concentrically positioned as regards their respective valve stems. These dials 30 are provided with any desired number of peripheral characters and are designed to form a safeguard against the unauthorized placing of the valve bores 16 in alinement with the valve casing bore 13 since the operator of the turning members 29 can only be assured that all of the valves are in the necessary alinement in which fuel is permitted to flow through the conducting fuel pipe 33 by the position assumed by 40 the pointers 30 with respect to the dials 32, such pointers having been previously adjusted so that their position immediately over any particular character on the dials 32 will be coincident with the alinement of the valve bores 16 with the casing bore, as 45 may be readily determined at the time of installation of the device.

Illustrated in Fig. 4 there will be seen a device substantially similar to that which 50 has just been previously described with one main difference, which is that the valve casing 12 is not positioned interiorly of the fuel tank but is provided with offset ends 35 whereby it may be interposed between spaced sections 36 of the fuel tank by means of the sleeve connections 37. In other respects the structure shown may be considered as substantially the equivalent of that previously disclosed but it possesses this great 55 point of advantage over the first described structure in that it may be positioned at any point which may be found desirable from the standpoint of convenience to the operator, providing only that leads from 60 the fuel pipe are connected respectively to

the offset ends 35 so that communication between the fuel tank and the motor must be established through the valve casing 12.

The offsetting of the ends 35 is particularly designed to prevent fraudulent attempts to so tamper with the valves as to obviate the necessity for previous knowledge of the combination as determined by the permutation dials 32 and also enables the provision of a straight bore 16 through the 75 valve plugs 15 instead of the V or Z-shaped bores previously considered necessary in devices of this character and accordingly cheapening to a great extent the cost of manufacture of the device. Hardened and 80 exteriorly threaded plugs 38 are provided as shown in the bosses 20 of the second form and are cut off flush in order to defeat any attempts to manipulate the extensions 21 of the valves. It will accordingly be seen 85 that by means of the simple yet efficient structure described in the foregoing that means have been provided capable of attaining the previously set forth objects and that this invention may accordingly be 90 claimed as presenting the advantages and desirabilities obviously inherent in the accomplishment of such objects.

While in the foregoing however, there has thus been illustrated in the drawings and 95 described in the specification such combination and arrangement of elements as constitute the preferred embodiment of this invention, it is desired to emphasize the fact that such minor changes in the matters of 100 proportion and degree may be made in later adaptations of this device as shall not alter the spirit of the invention as defined in the appended claims.

What is claimed is:

1. The combination with a tank formed with a depression in the bottom thereof, of means for controlling the discharge from said tank including a casing positioned within said depression and leading from the tank, a longitudinal bore in the casing, valves provided with registering bores to intersect the casing bore, a stem for each valve projecting through the upper portion of the tank, and permutation means associated with each individual valve stem.

2. The combination with a fuel tank having an offset portion formed in the bottom thereof, of a valved casing seated in said offset portion, flanges formed on said valved casing for securement to said tank, valves rotatably positioned within said casing, extensions for said valves, resilient means co-operating with said extension to correctly seat said valves, stems for said valves, dials surrounding said stems, and means coacting with said dials and adjustably mounted upon said stems to indicate the position of each separate valve.

3. The combination with a fuel tank hav-

ing an offset portion formed in the bottom thereof, of a valve casing provided with a longitudinal bore and positioned in said offset portion, transversely bored rotatable valves mounted in said casing to intersect the bore of the latter and to form means for interrupting or continuing said bore, stems for said valves, turning members for said stems, dials surrounding said stems relatively fixed thereto, adjustable collars mounted on said stems, pointer extensions formed on said collars to coact with said dials in indicating the position of said valved bores, and a conveying pipe communicating with said casing bore at one end and adapted to conduct fuel from the tank that has passed all of said valves.

4. The combination with a tank having a depression formed in the bottom thereof, of means for controlling the discharge from the tank including a casing, arms straddling the depression to support the casing therein, an offset end leading from the casing through the bottom of the depression, a longitudinal bore in the casing being connected with a similar bore through the offset end, a plurality of valves intersecting the lon-

gitudinal bore and provided with registering bores, a stem for each valve projecting through the tank, a packing cup for each valve stem provided on its upper face with characters, and a pointer adjustably mounted upon each valve stem to coact with respective characters in determining the opening of the bore.

5. The combination with a tank, of means for controlling the discharge from said tank including a casing positioned in the bottom of said tank, said casing having a longitudinal bore, a plurality of valves intersecting the longitudinal bore and provided with registering bores, a stem for each valve projecting through the tank, a packing for each valve stem provided on one face with characters, and a pointer adjustably mounted upon each valve stem to co-act with respective characters in determining the opening of the bore.

In testimony whereof I affix my signature in presence of two witnesses.

JAMES R. BURKHARDT.
